STORAGE TANK TOY

Robert D. Pfister, Westport, Conn., assignor to De Luxe
Reading Corporation, Elizabeth, N.J., a corporation of
New Jersey

Filed Mar. 16, 1965, Ser. No. 84,298

Term of patent 3½ years

(Cl. D34—15)

FIG. 1

FIG. 2

FIG. 3

FIG. 4

FIGURE 1 is a perspective view of a storage tank toy, showing my new design;

FIGURE 2 is an end view thereof;

FIGURE 3 is a top plan view thereof;

FIGURE 4 is a side elevational view thereof.

I claim:

The ornamental design for a storage tank toy, substantially as shown.
